UNITED STATES PATENT OFFICE.

JOHN E. BELL, OF BROOKLYN, NEW YORK, ASSIGNOR TO POWER SPECIALTY COMPANY, OF NEW YORK, N. Y., A CORPORATION OF NEW YORK.

OIL HEATER.

Application filed July 3, 1920. Serial No. 393,901.

To all whom it may concern:

Be it known that I, JOHN E. BELL, a citizen of the United States, residing at Brooklyn, county of Kings, and State of New York, have invented certain new and useful Improvements in Oil Heaters, of which the following is a full, clear, and exact description.

In an application filed by me on June 10, 1920, Serial No. 387,970, I have shown oil heaters in which the heating chamber was divided into a forward and a rear compartment by a bridge wall, and in which there are arranged two banks or groups of pipes or tubes for conveying the oil. One of these banks is placed in the compartment more remote from the fire, and the other and smaller bank in the upper part of the other compartment. 10

The cold oil is introduced into the first named bank at the bottom and flows upwardly through its tubes in a direction counter to the current of hot gases which flow over the bridge-wall and downward in the remote compartment on their way to the flue. This bank of tubes is connected in series with the other, preferably to the bottom of the same, as the oil on reaching such second bank is at a temperature which renders it unnecessary to cause it to flow through said bank counter to the flow of the hot gases which sweep its tubes.

Upon this general type or form of heater the invention, subject of my present application, is an improvement. It is an improvement in the following particular.

It is desirable that the tubes of both banks should extend horizontally in as great lengths as possible, but the ordinary plan of construction prohibits the use of very long lengths of tube, by reason of the difficulty of properly supporting the same and preventing them from sagging. This defect I remedy by building in both chambers transverse bridge walls which afford central supports for the banks. I further provide for the independent support of the horizontal rows or layers of tubes by supporting cantilever bars or rods embedded in one wall of the compartment and forming what may be regarded as shelf supports for said rows of tubes.

It is also desirable that the flow of oil through the heater should be slow and not as rapid as it would ordinarily be if forced

through the tubes in series, and it is further more desirable that its path through the heat absorbing tubes should be as long as practical conditions will permit. For this purpose, I divide the banks into two main paths in parallel, each path having all of its tubes connected in series, and each series being connected to the source of supply from which the oil is delivered under the proper pressure.

These are the main features of novelty of the invention, and are illustrated in the accompanying drawings:

Fig. 1 is a section of the structure embodying the invention on the line 1—1 of Fig. 2, and

Fig. 2 is a similar but broken section of the same on the line 2—2 of Fig. 1.

The structure, as a whole, is built in the known manner with heat-resisting and, preferably, heat-insulated walls 1. The heating chamber is divided into forward and rear compartments 2, 3, by a bridge wall 4, and in the lower part of the forward compartment is the fire box or furnace of any suitable character.

Centrally in the forward compartment is built up a wall 5, of refractory material, and centrally in the other compartment is built another but much lower wall 6.

Upon the wall 5 is supported a bank of tubes 7, and upon the wall 6 is similarly supported a bank of tubes 8. The tubes in these banks, as shown in Fig. 2, are much longer than usual, but the support afforded by the walls 5 and 6 effectually prevents sagging.

As an additional support for the tubes of each bank, rectangular rods of cast iron or other suitable material 9 are embedded in the side walls of the furnace at three or more points, the said rods being preferably in vertical rows and extending out under all of the horizontal rows of oil tubes, as shown in Fig. 1. I prefer to employ tubes, encased in cast iron rings, and commonly known as Foster elements, but where the rods 9 contact with said tubes the rings are omitted, and this is indicated in the drawings.

These rods form shelves upon which the horizontal rows of tubes rest. The lowermost rods may rest upon the supporting walls 5 and 6, as shown, and this affords additional and firm support. The rods not

only prevent sagging, but permit any one or more horizontal rows of tubes to be removed bodily, when necessary for repair or other reasons, without disturbing any of the other rows in the bank because the rods constitute shelves which aid in the support of the horizontal rows of tubes, and if any row of such tubes be removed these supports may be strengthened by interposed blocks.

10 Removal of a tube in a bank or a number of tubes in a particular horizontal bank is effected as follows: Upon ascertaining that a particular tube is to be removed the headers of this tube are first cut off. The rods

15 9 are primarily supported at one end in the brick-work 1^a of the furnace and their ends extend into the insulating packing material marked 1 in Fig. 1. Covering this insulating packing material is a door designated

20 14 (see also dotted line rectangles in Fig. 2). Before or after the header is cut off the doors 14 are removed and the packing material is dug away from around the end of the particular rod 9 which is below

25 the tube or tubes which are to be removed. Rod 9 is then drawn out (i. e. to the right in Fig. 1). The tube is now ready for removal except that inasmuch as the corrugations of one tube overlap the next super-

30 imposed rod 9 it is necessary that the tube which is to be removed be lowered before such removal is effected. To effect such preliminary lowering of the tube the end plates 15 which are of the usual square

35 rectangular construction slidably mounted upon each tube are slid endwise out of co-operation with the cooperating lower rectangular plates. This permits the selected tube to be lowered bodily to a sufficient ex-

40 tent to clear it from interference with the next higher rod 9. The whole tube assembly can then be redrawn endwise out of the tube chamber.

45 Each horizontal row of tubes in the present case is shown as composed of six elements, an arbitrary but convenient number, and the entire bank in each compartment is divided into two sets or groups of tubes. The tubes in each half or group are connected together in series, while each group

50 of tubes is connected with the pipe or header that introduces the oil in multiple. In the present case the two sets of tubes in the bank 8 are connected to the inlet

55 pipe 10 at the bottom of the bank and the two sets of tubes in the bank 7 are connected with the pipe 11 that leads from the top of the first named bank. At the top of bank 7, the two sets of tubes are

60 connected to the outlet pipe 12.

For this arrangement the capacity of the

By this arrangement the capacity of the

passage for oil through the device is very largely increased, which results in a reduction in the rate of flow. But as the tubes of each set are connected in series, one with another, a relatively long path for the oil is provided. 65

In other respects than those herein noted, the construction of the device is largely immaterial. The arrangement described is highly efficient and has to recommend it its great simplicity and the means which it affords for easy access to the tubes or elements for removal, if need be. 70

What I claim is:

1. In an oil heater, the combination with heating chambers, of banks of tubes in long horizontal lengths therein, bridge walls built transversely in said chambers upon which, as substantially central supports, the lower tubes of said banks rest, and means independent of said bridge walls for independently supporting all of the upper sets of tubes above said transverse walls to prevent sagging of the same when highly heated. 80 85

2. In an oil heater, the combination with banks of tubes in long horizontal lengths of supporting cantilever rods extending transversely relative to the said tubes and forming shelf supports for the individual horizontal rows of such tubes, said rods being embedded in and projecting from one of the side walls of the chamber.

3. In an oil heater, the combination with 95
a heating chamber divided by a bridge
wall into a forward and a rear compart-
ment, a bank of long horizontal tubes in
each compartment, transverse bridge walls
in each compartment forming central sup-
ports for said banks of tubes, and cantilever
rods or bars embedded in the front
and rear walls of the two parts of the
chamber respectively and extending toward
the first mentioned bridge wall transversely
of the tubes and forming shelf-supports for
the individual horizontal rows of the tubes
of each bank. 100 105

4. In an oil heater, the combination with
banks of tubes in long horizontal lengths 110
with headers at their ends, of rods sup-
ported at one end only in the wall of the
furnace and projecting therethrough so as
to be removable from without the furnace,
said rods each forming a shelf-like support
for a bank of the tubes and adapted upon
removal to permit the endwise removal of
said bank of tubes or the removal of any
tube unit thereof. 115

In testimony whereof I hereto affix my signature.

JOHN E. BELL.
